UNITED STATES PATENT OFFICE.

SEARCHED SERIALIZED INDEXED OFFICE

SIDNEY WRIGHT, OF BROOKLYN, NEW YORK.
ROAD-PLANER.

1,272,756.

Specification of Letters Patent. Patented July 16, 1918.

Application filed May 3, 1915, Serial No. 25,456. Renewed May 6, 1918. Serial No. 232,938.

To all whom it may concern:

Be it known that I, SIDNEY WRIGHT, a citizen of the United States, residing at Brooklyn, in the county of Kings and State 5 of New York, have invented certain new and useful Improvements in Road-Planers, of which the following is a specification.

This invention relates to improvements in machines for scarifying and planing the 10 surfaces of roadways, and it comprises attachments, which may, with modifications, be applied to various types of bodies of road scarifying machines, but which are adapted more particularly to the type of scarifying 15 machines illustrated in my co-pending application, Serial No. 863,737, in which the teeth of the scarifier are held firmly down to

opposite directions. In the drawing, the picks 8 are shown as pointed scarifying picks, while the picks 9 are cut off at the 60 bottom at an angle of 45°, as shown at 9a, for planing purposes. It will be understood, however, that planing picks may be placed in both ends for some classes of work where it is desired to pass over the roadway 65 in both directions and plane at each operation; but at times, it may be desirable to use the pointed scarifying picks on one end of the machine and the planing picks at the other, and they are so shown for the purpose 70 of illustration in the drawing.

Hawse-holes or passageways a and a' are provided in the upper portions of the end walls of the body, these passageways being substantially radial to the axis of the axle 75

and the first contact with the spiritual plane. The first step is to learn to control the physical organism, especially the breath, which is the chief factor in the development of the spiritual body. Breath control is the first step in spiritual development, as the physical body is the vehicle of the spiritual body.

... wanted to re-establish himself and his family, and he had to leave.
